UNITED STATES PATENT OFFICE.

LOUIS B. SMYSER, OF PHILADELPHIA, PENNSYLVANIA, ASSIGNOR TO ARTHUR M. KENNEDY, OF PHILADELPHIA, PENNSYLVANIA.

CAR-FENDER.

1,237,833.

Specification of Letters Patent. Patented Aug. 21, 1917.

Application filed January 8, 1917. Serial No. 141,184.

To all whom it may concern:

Be it known that I, LOUIS B. SMYSER, a citizen of the United States, residing in Philadelphia, Pennsylvania, have invented 5 certain Improvements in Car-Fenders, of which the following is a specification.

My invention relates to a drop fender of the type shown in U. S. Patent No. 1,212,071, dated January 9, 1917, the present invention 10 comprising certain modifications of constructive detail intended to simplify and cheapen the construction of the fender, to provide for locking the same in the lowered position after it has been dropped, and to 15 vary the extent of forward projection of the lower portion of the dropped fender.

In the accompanying drawing—

Figure 1 is a side elevation of the fender structure showing the movable member of 20 the same in the raised position;

Fig. 2 is a similar view showing said movable member in the dropped position;

Fig. 3 is a perspective view of the fixed members of the fender and of parts of the 25 top and bottom bars of the frame of the movable member, and

Fig. 4 is a side view of certain parts of the fender designed to vary the extent of forward projection of the dropped fender.

In the drawing, 1—1 represent the forwardly projecting ends of the opposite side frames of a motor car, upon which are fixedly supported by means of angle plates 2 opposite side plates 3. In said side plates 30 3 are formed bearings for upper and lower rock shafts 4 and 5, the upper shaft 4 being provided near each end with a depending hook 6 pressed forwardly by means of a spring 7 and the lower shaft 5 being provided near each end with a depending latch 8 normally pressed forward by means of a spring 9. The rock shaft 4 is also provided with a depending arm 10 which has suitable connection 11 with a bell crank lever 40 12 pivotally mounted on the car body, and in operative connection with a plunger 13 therein, said plunger, by preference, bearing such relation to the brake pedal 14 that both can be operated by one and the same 45 15 foot.

Extending across the machine in advance of the plates 3 is a frame 17 which may be provided with any desired form of screen or netting 18 (Figs. 1 and 2) this frame 17

preferably projecting laterally beyond the 55 side plate 3 to such an extent as to screen the forward wheels of the car. Each of the top bars of the screen frame 17 has a rearwardly projecting fork 19 which embraces its respective side plate 3, the opposite limbs 60 of each fork being connected by a pin 20 which is free to slide vertically in a slot 21 in said side plate 3.

Extending between the side members of the frame 17 is a shaft 15, to which is either 65 fixedly or pivotally connected the lower ends of a pair of rearwardly extending and upwardly inclined bars 22, one adjacent to each side plate 3, each of these bars being free to slide between forward and rear pairs of rollers 23 and 24, being mounted so as to be free 70 to rotate on the respective side plate 3.

Rotatably mounted upon each of the side plates 3 in advance of the rollers 23 and 24, and in the forward line of travel of the 75 under side of the bar 22 is a supporting roller 25. The lower bar of the frame 17 has secured to it rearwardly extending plates 26 in which rollers 27 are mounted so as to be free to rotate, as shown in Fig. 2. 80

When the frame 17 is in the elevated position shown in Figs. 1 and 3 the inner limbs of the forks 19 are engaged by the spring pressed hooks 6 and said frame 17 is thereby supported in such elevated position. When it is desired to drop the fender, however, the driver of the car depresses the plunger 13, thereby retracting the hooks 6, the upper end of the frame 17, during the drop of the same, being held close to the 90 forward edges of the side plates 3 by reason of the engagement of the pins 20 with the slots 21 in said side plates but the lower end of the fender being projected forwardly by reason of the engagement of the inclined 95 bars 22 with the pairs of rollers 23 and 24, the roller 25 acting as an additional support for the bar 22 soon after the fender starts to drop, and the rollers 27 coming into contact with the roadway as soon as the 100 fender reaches its fully lowered position.

When the fender is fully lowered the inner members of the forks 19 are engaged by the spring actuated catches 8, as shown in Fig. 2, and the fender is thus prevented 105 from rising until these catches are withdrawn by means of a handle 28, on the rock shaft 5, whereupon the fender can be again

lifted to the raised position shown in Fig. 1 and retained in such position by the spring hooks 6.

The rearwardly projecting members 19 on the fender frame may, as will be evident, be single instead of forked, although the latter form is preferred because of the stronger support for the pins 20 which is thus provided.

10 The fender shown in Figs. 1, 2 and 3 has a fixed extent of forward projection as it drops, but if it is desired to vary such extent of projection the angular relation of the rollers 23 and 24 may be changed so 15 as to change the angle of projection of the bars 22. One means of effecting such change is shown in Fig. 4, the bar 22 therein being pivoted to the shaft 15, and the rollers 23 and 24 being rotatably mounted upon 20 pivot pins which are adjustable in curved slots 30 formed in the side plates 3.

I am aware that previous to my invention a fender has been devised in which the fender carrying frame was pivotally mounted, 25 upon brackets extending forwardly from the opposite ends of a transverse bar guided in its vertical movements by means of vertical slots in the side plates of the fender structure, said fender frame having also connected to its lower ends upwardly and rearwardly inclined bars which were guided in similarly inclined boxes on said side plates.

By engaging the pivot pins of the fender frame directly with the vertical slots in the 35 side plates, however, I dispense with the transverse bar employed in the structure referred to and by substituting guide rolls for the box-like guide employed in said previous structure I insure free movement of said 40 guide bars at all times, overcome any tendency of the guide bars of the fender frame to stick fast in the guides because of accumulations of rust or dirt therein, and provide for varying, as desired, the extent of 45 forward projection of the dropping fender.

I claim:

1. The combination, in a fender for motor cars, of side plates each having a vertical slot therein and guide rollers rotatably 50 mounted thereon, and a fender frame having at its upper end pivot pins engaging said slots and at its lower portion rearwardly and upwardly inclined guide bars engaging said guide rollers.

55 2. The combination, in a fender for motor cars, of side plates each having a vertical slot therein and upper and lower guide rollers rotatably mounted thereon, and a fender frame having at its upper end pivot pins engaging said slots and at its lower portion

rearwardly and upwardly inclined guide bars sliding between said upper and lower guide rollers.

3. The combination, in a fender for motor cars, of side plates each having a vertical slot therein and upper and lower pairs of guide rollers rotatably mounted thereon, and a fender frame having at its upper end pivot pins engaging said slots and at its lower portion, rearwardly and upwardly inclined 65 guide bars sliding between said upper and lower pairs of guide rollers.

4. The combination, in a fender for motor cars, of side plates each having a vertical slot therein and guide rollers rotatably 75 mounted thereon, and a fender frame having at its upper end pivot pins engaging said slots and at its lower portion rearwardly and upwardly inclined guide bars 80 engaging said guide rollers, said fender frame also having, at the bottom, supporting rollers for traveling on the roadway when the fender frame is dropped.

5. The combination, in a fender for motor cars, of opposite side plates, and a fender 85 frame vertically movable in respect thereto and guided in its vertical movements thereby, hooks for engaging said frame and holding it in elevated position, latches for engaging the frame and preventing it from 90 rising after it has been dropped, and means for projecting and retracting said hooks and latches.

6. The combination, in a fender for motor cars, of side plates each having a vertical 95 slot therein and guide rollers mounted thereon, and a fender frame having at its upper end pivot pins engaging said slots and at its lower portion rearwardly and upwardly inclined guide bars 100 engaging said guide rollers, and means for changing the angular relation of the latter in respect to one another so as to vary the extent of forward projection of the dropping fender.

7. The combination, in a fender for motor cars, of side plates each having a vertical slot therein and front and rear pairs of guide rollers mounted thereon, a fender frame having at its upper end pivot pins engaging said slots and at its lower portion rearwardly and upwardly inclined bars sliding between said front and rear pairs of rollers, and means for changing the angular relation of the front and rear pairs of rollers in respect to one another so as to vary 115 the extent of forward projection of the dropping fender.

In testimony whereof, I have signed my name to this specification.

LOUIS B. SMYSSER.
